UNITED STATES PATENT OFFICE

124,172

DESIGN FOR A DRESS ENSEMBLE

Sabina De Pasquale, Flushing, N. Y.

Application September 26, 1940, Serial No. 95,387

Term of patent 3½ years

To all whom it may concern:

Be it known that I, Sabina De Pasquale, a citizen of the United States, residing at 146-24 33rd Ave., Flushing, Long Island, in the county of Queens and State of New York, have invented a new, original, and ornamental Design for a Dress Ensemble, of which the following is a specification, reference being had to the accompanying drawing, forming part thereof.

Figure 2 is a front view of the dress alone; Figure 3 is a rear view of the same; and Figure 4 is a rear view of the jacket.

The characteristic feature of my design resides in the combination on the dress ensemble disclosed, of the specific embroidered jacket member, as shown.

I claim:

The ornamental design for a dress ensemble, substantially as shown and described.

SABINA DE PASQUALE.
